SPENCER H. OSTROM, OF SCHENECTADY, NEW YORK.

Letters Patent No. 90,292, dated May 18, 1869.

IMPROVEMENT IN HAND-DRILLS.

The Schedule referred to in these Letters Patent and making part of the same.

To all whom it may concern:

Be it known that I, SPENCER H. OSTROM, of Schenectady, in the county of Schenectady, and State of New York, have invented a new and useful Improvement in Boring-Braces; and I do hereby declare the following to be a full, clear, and exact description thereof, which will enable those skilled in the art to make and use the same, reference being had to the accompanying drawing, forming part of this specification, in which drawing—

Figure 1 represents a sectional side elevation of this invention.

Figure 2 is a sectional plan thereof.

Similar letters indicate corresponding parts.

This invention consists in the arrangement of a friction-strap, having one of its ends fastened to the handle, and its other end to a swivel-arm, to which the handle is pivoted, and which turns loosely on the head of the brace, said friction-strap being made to embrace the head of the brace, in such a manner that by moving the handle in one direction, the strap is made to clamp the head, and said head, together with the bit, or drill inserted therein, is compelled to turn, and by moving the handle in the opposite direction, the strap releases the head of the brace, and the bit, or drill remains stationary, while the handle is swung back ready for a subsequent motion.

A spring attached to the swivel-arm, and bearing on a stud rising from the handle, compensates for all lost motion of the handle.

A represents the head of my brace, which is provided with a socket, *a*, to receive the bit, or drill, and from which extends the screw *b*, which is tapped into the cap *c*, and serves to produce the requisite feed-motion of the drill.

To the head *A* is fitted the swivel-arm *B*, which turns loosely thereon, and which connects, by a pivot, *d*, with the handle *C*.

To the inner end of this handle is secured one end of a strap, *e*, which passes round the head *A*, and has its other end fastened to the swivel-arm *B*, as shown in figs. 1 and 2 of the drawing, so that by turning or moving the handle in the direction of arrow 1, the strap is caused to clamp the head, and thereby said

head is compelled to turn with the handle, but by swinging the handle in the direction of arrow 2, the strap releases the head, and the handle turns, while the head remains stationary.

The strap *e* is, by preference, made of spring-steel, and it is so applied that its inherent elasticity will keep the handle in proper position to prevent lost motion in the implement, but said strap may be made of any suitable flexible material.

An additional spring, *f*, which is secured in the swivel-arm *B*, and bears against a stud, *g*, projecting from the handle *C*, serves to throw the handle in such a position that the strap *e* clamps the head *A*, and by these means all dead motion of the implement is avoided.

By this arrangement, a boring-brace is produced which works perfectly noiseless, and which has the further advantage, over the ordinary ratchet-brace, that the whole forward motion of the handle, whether large or small, is transmitted to the bit or drill, whereas, in ordinary ratchet-braces, it happens frequently that the handle cannot be, or is not moved back far enough to cause the pawl to drop down closely behind the new tooth, and thereby the operation of the brace is rendered disagreeable, and sometimes difficult; and, furthermore, by the slipping of the pawl on the ratchet-teeth, and by the blows created when the pawl strikes a tooth, the working-parts of the brace are caused to wear out in a short time.

My brace can be used in any place where the handle can be moved back and forth, whether the motion allowed to said handle be large or small, and the full motion of the handle is always transmitted to the drill.

Having thus described my invention,

What I claim as new, and desire to secure by Letters Patent, is—

The spring *f*, in combination with the strap *e*, head *A*, swivel-arm *B*, and handle *C*, substantially as set forth.

SPENCER H. OSTROM.
